UNITED STATES PATENT OFFICE.

VICTOR ADLER, OF ST. LOUIS, MISSOURI, ASSIGNOR OF ONE-HALF TO A. J. SOMERVILLE, OF SAME PLACE.

DESIGN FOR AN EASEL.

SPECIFICATION forming part of Design No. 22,587, dated July 4, 1893.

Application filed March 13, 1893. Serial No. 465,827. Term of patent 14 years.

To all whom it may concern:

Be it known that I, VICTOR ADLER, of the city of St. Louis and State of Missouri, have invented a certain new Design for Mantel Ornaments, of which the following is a full, clear, and exact description, reference being had to the accompanying drawings, forming a part hereof.

Referring to the drawings, Figure 1 is a front elevation of an easel embodying my design. Fig. 2 is a side elevation of the same.

1 indicates the body of the design, the same being in the form of a triangular figure having a raised border 2, and divided into three 15 separate sections, each of which has a substantially triangular outline.

3 indicates elevated partitions, which divide the triangular figure into sections. The front surface of each section is roughened or 20 irregular.

The body 1 is mounted upon a base 4, comprising three steps, 5, 6 and 7 of rectangular contour, increasing in length downward, so that the lower step of the series has the greatest length, and each of said steps being located a little in the rear of the next lower step. On the next adjacent step 6 intermediate of its length is located a raised figure of 25 a skull and cross-bones.

Surmounting the triangular body 1 is the 30 raised configuration of a helmet 8 patterned after those worn by sir knights of ancient history, and surmounting said helmet is the configuration of a bird of prey 9.

Projecting outwardly at diverging angles, 35 above the triangular body 1 are opposite facing figures 10 representing battle-axes, the handles 11 of which are represented as crossing each other with their ends projecting outward and free.

Upon the rear face of the triangular body 1 is located a projection 12, from which depends a slender body 13 so that the lower end of said slender body rests in the plane of the lower edge of the lower step.

14 indicates the design complete.

What I claim is—

The design for an easel as herein shown and described.

In testimony whereof I affix my signature in 50 presence of two witnesses.

VICTOR ADLER.
